United States Patent Office

Des. 184,202
Patented Dec. 30, 1958

184,202

CHAIR

Akron S. H. Yuen, Shumshuipo, Kowloon,
Hong Kong, China

Application January 23, 1957, Serial No. 44,558

Term of patent 14 years

(Cl. D15—1)

Fig. 1 is a perspective of a chair showing my new design;

Fig. 2 is a side elevation of the chair of Fig. 1; and Fig. 3 is a top plan view of the chair of Fig. 1; Fig. 4 is a rear perspective view of the chair of Fig. 1. I claim:

The ornamental design for a chair, as shown.
